(57) **CLAIM**

The ornamental design for a running board, as shown and described.

DESCRIPTION

FIG. 1 is a perspective view of a running board according to the present invention shown attached to a motor vehicle.

FIG. 2 is a top view of the running board of FIG. 1.

FIG. 3 is a front view of the running board of FIG. 1.

FIG. 4 is an end view of the running board of FIG. 1.

FIG. 5 is a perspective view of a second embodiment of a running board according to the present invention shown attached to a motor vehicle.

FIG. 6 is a top view of the running board of FIG. 5.

FIG. 7 is a front view of the running board of FIG. 5; and, FIG. 8 is an end view of the running board of FIG. 5.

FIGS. 2-4 and 6-8 are shown on an enlarged scale as compared with FIGS. 1 and 5 respectively.

The vehicle shown in the drawings in broken lines does not form a part of the invention. In addition, the views of the running board that are not shown in the drawings do not form a part of the invention.

1 Claim, 4 Drawing Sheets
